TURBODISSOLVER

Clarence R. Rechtin, Bridgetown, and John E. Trostle, Cincinnati, Ohio, assignors to The J. H. Day Company, Cincinnati, Ohio, a corporation of Ohio

Application October 6, 1943, Serial No. 505,146

7 Claims. (Cl. 259—96)

The present invention relates to a machine, referred to herein as a turbo-dissolver, for cutting and mixing a soluble material with a solvent so as to produce a homogeneous mass.

One of the principal objects of the invention is to provide a turbo-dissolver with such improvements as will greatly expedite the production of a solvate, or a mixture, composed of fluid and solid materials, thereby resulting in substantial savings of time, labor, and expense in the processing of such materials.

Another object of the invention is to provide a machine of the character stated, which includes a combined agitating, cutting, and circulating means, for the effective processing of materials to produce a desired solvate.

Another object of the invention is to produce a simple yet highly efficient machine for the purpose stated, having a minimum number of moving parts sturdily constructed and arranged in such fashion as to reduce to a minimum the possibility of breakage and distortion of parts, so that the machine may operate for extended periods of time without need for repairs or servicing.

A further object is to provide a novel and efficient form of impeller for a machine of the turbo-dissolver type.

The foregoing and other objects are attained by the means described herein and disclosed in the accompanying drawings in which:

Fig. 1 is a side elevational view of the turbo-dissolver, part being broken away to show the interior.

Fig. 2 is a cross sectional view taken on line 2—2 of Fig. 1.

Fig. 3 is a side view of the impeller element of the machine.

Fig. 4 is a fragmental cross sectional view of a shearing impeller blade which forms part of the impeller element.

Machines of the general character herein disclosed have been constructed in various ways, with the hope of reaching the highest possible degree of efficiency, particularly with relation to the extent of the mixing period. Various forms of impellers have been devised, operating at various rates of speed and within unique environments, and in the effort to reduce to a minimum, the time period required for the production of a solvate or uniform mixture, from soluble solid material and a suitable solvent therefor. As a general rule, the production of a satisfactory solvate or homogeneous mixture requires many hours of mixing time, resulting in comparatively slow pro-

duction and a correspondingly increased expenditure of labor and power, accompanied also by frequent servicing and repairs in the machine.

The present invention has overcome the foregoing obstacles, to expedite and speed up production to a very material extent. Instead of merely churning up the solute and the solvent until a homogeneous mixture or compound is secured, the present machine incorporates with its churning action a rapidly operating comminuting or shredding action along with the circulating and churning of the constituents of the mix. Moreover, the circulating action imposed upon the substances undergoing processing, is rendered severe to an extent heretofore unobtainable with the use of known mixing machines. It has been determined that the mixing period in many instances may be reduced by 300%, without impairing the quality or the thoroughness with which the solvate is produced.

Referring to the accompanying drawings, Fig. 1 illustrates the improved machine, which comprises a large cylindrical tank 6 supported in any suitable manner, such as by means of legs or standards 7, and within which is mounted an impeller indicated generally by the character 8. The impeller is adapted to be rotated by means of a vertical shaft 9 driven from any suitable source of power, herein represented as an electric motor 10, through the medium of a train of gears housed within the gear box 12. The driving means may be properly supported upon brackets 13 or otherwise, above a tank cover 14 which has a charging port indicated at 15. The nature of the tank cover, the charging port and the driving means, is a matter of immateriality to the present invention, and may accordingly be designed in accordance with common practices in manufacturing procedure.

As will be understood, the impeller shaft 9 is supported for rotation vertically, with the aid of suitable bearings 16 and 17 located at the upper and lower ends of the tank. The impeller 8 may be keyed or otherwise suitably fixed upon the impeller shaft, as at 18, and is preferably so located as to rotate centrally of tank 6. The region in which the impeller rotates is defined by a stationary knife assembly, which comprises a series of radially extending blades 19, each of which carries an inwardly directed upright or shearing edge 20. The back edges of the knives are indicated at 21, and are spaced from the side wall of the tank upon mounting bases 22 adapted for securing of the knife assembly to the bottom wall 23 of the tank. The connections between

the tank bottom and the bases of the knives may be effected in any suitable manner, such as by means of screws or bolts 24 which securely mount the bases relative to a locating pad illustrated at 25.

The extreme upper edges of the knives may be supported by a circular connector ring 26, within the confines of which the rotating impeller is operative. As illustrated by the reference characters 27 of Fig. 2, each knife 19 may be reinforced against possible distortion or breakage, the characters 27 representing suitable reinforcing struts or webs extending from the connector ring 26 downwardly to the several knife mounting bases. The knives preferably are arranged radially upon the tank bottom, and will preferably, though not necessarily, be located in vertical planes which intersect the axis of the impeller shaft. The series of knife edges and the connector ring of the stationary knife assembly provide a well centrally of the tank, within which a major portion of the impeller may be rotated.

The impeller itself is likewise of well shape, and comprises a bottom wall 28 of shallow cone shape carried by the hub 29 and elevated slightly above the tank bottom. The impeller bottom may be furnished with a series of openings indicated at 30, the purpose of which will be explained. The lower end of the impeller hub may rest upon a suitable thrust bearing 31, to maintain a desired elevation of the impeller within the well established by the stationary knife unit.

The upper surface of the impeller bottom 28 carries a series of shearing impeller blades 32, which as illustrated by Fig. 2 are curved backwardly, or oppositely to the direction of rotation of the impeller proper. These blades are each constituted of an upright shearing or knife section 33, and a radially curved centrifuging section 34, preferably integral with one another. Both sections are inclined to the vertical, in the direction of rotation of the impeller, so that the leading faces of the blades will have top edges 35 (Fig. 2) arranged in advance of the lower edges 36, whereby upon rotation of the impeller in the direction of the arrow 37, the material undergoing processing will be drawn downwardly into the central well of the impeller, as indicated by the series of arrows 38 upon Fig. 1, and thrown outwardly toward the tank wall. As will be evident from an observation of Fig. 1, most of the material thusly circulated will be forced to escape through the shearing region of the knives, where comminution of any solid particles of the material takes place. The outer edges of the knife sections 33 are sharpened or provided with suitable cutting areas at the locations 39, the sharpened edges extending substantially the full length of the stationary knives 19.

Fig. 4 shows one of the shearing impeller blades 32 provided with a cutting edge 39, which may be formed as a weld of hard and durable metal applied to the leading face 35 of the blade. It will be understood, of course, that a sharp edge may be furnished at the end of the blade, without resorting to a weld such as is illustrated at 39 of Fig. 4.

The series of shearing impeller blades may be supported at their upper ends by means of a circular impeller ring 40, which ring preferably is located at approximately the same elevation as the stationary knife unit ring 26. The inner circumferential edge 41 of the impeller ring may

be flared inwardly and upwardly as indicated, for the purpose of inducing a free and direct flow of solvate to the central well of the rotating impeller. A series of upstanding elevated vanes 42 may project above the impeller ring, the number of such vanes being sufficient to insure a high degree of turbulence above the impeller, for the two-fold purpose of aiding the mixing action, and keeping the flat surfaces of both rings clear of any sediment or adhering matter in the mixture undergoing processing.

As previously mentioned, the bottom wall of the impeller carries a series of perforations 30. These perforations serve to drain the impeller upon completion of the mixing operation, so that all of the solvate may be drained from the tank and from the impeller through the flush valve 43. In order that none of the solvate may remain static or isolated beneath the bottom of the impeller during the mixing operation, the underface of the impeller bottom preferably is provided with a series of sweep fins 44 which radiate outwardly from the impeller hub 29 to reach the outer limits of the impeller bottom. The sweep fins may be curved correspondingly with the curvature of the shearing impeller blades so as to produce a substantial centrifuging action upon the solvate. The lower edges 45 of the sweep fins preferably are made arcuate in conformity with the concavity of the tank bottom, along which the sweep fins travel with slight clearance.

In the operation of the turbo-dissolver, a solvent is introduced into the tank along with sheets, strips, or chunks of soluble material to be dissolved, and as the driving means is placed in operation, the solvent will immediately proceed to circulate in the orbit indicated by the arrows 38 of Fig. 1. The solid material to be dissolved will be carried downwardly into the central well of the impeller, and will be repeatedly introduced to the rotating and stationary knife edges 39 and 20, where complete and powerful forces are imposed for cutting up and comminuting the solid material. By shredding or shearing the solid material into a multitude of particles, and subjecting the particles to the turbulent action of the impeller, a rapid disintegration of the solid material occurs so as to substantially increase the area of solid material exposed to the action of the solvent. The longer the machine is operated, the smaller the particles of solid material will be comminuted, with the result that the formation of a homogeneous mass of solvent will be greatly expedited. Upon completion of the mixing operation, the interior of the tank and of the impeller may be drained completely of solvate through the flush valve 43.

In conclusion, it may be stated that the stationary knife assembly and the rotating impeller unit embody various structural features which render them highly durable and resistant to distortion or breakage, all of which is necessary due to the fact that the solid material to be dissolved is frequently introduced into the tank in the form of heavy sheets, strips, or chunks of varying sizes. The service required of the impeller and the knife assembly may be appreciated to some extent, when it is considered that the material to be dissolved may be crude rubber, or other forms of rubber, introduced into the tank as thick sheets or strips which are occasionally rolled up in ball formation.

It should be understood that the processing of certain materials may result in the generation of considerable heat, in which event the tank

may be surrounded by a jacket adapted to contain a coolant or possibly even a refrigerating coil. The cooling of the tank is particularly desirable when the solvent is of a volatile nature, and might therefore be lost in the presence of heat generated incident to the mixing process. In other cases, the mixing process might possibly be expedited by jacketing the tank 6 and introducing into the jacket a heating medium, or possibly a direct flame to elevate the temperature of the tank. It has been proposed also to apply electric heating elements either interiorly or exteriorly of the tank, in those instances requiring the application of heat in aid of the mixing operation. These considerations, while capable of rendering considerable assistance to the rapid production of a satisfactory solvate, are corollary to the action of the shearing, cutting, or shredding function, and also the material circulating effects induced by the improved means of the present invention.

It is to be understood that various modifications and changes in the structural details of the device may be made, within the scope of the appended claims, without departing from the spirit of the invention.

What is claimed is:

1. In a turbo-dissolver, the combination of a tank having a side wall and a bottom, a circular ring of stationary knives upstanding within the tank, said knives having back edges spaced from the side wall of the tank to provide an escape passageway for liquid-borne material undergoing processing within the tank, an open well in the tank defined by the knife edges and having as its bottom the bottom of the tank, an open topped impeller fitted within the well and arranged for rotation therein in a horizontal plane, said impeller having a bottom overlying the tank bottom, and a series of radially disposed blades supported above the impeller bottom and extending outwardly to close proximity with the circular ring of knives, the outer ends of the blades including shearing edges to cooperate with the ring of knives when the impeller is rotated, for comminuting solid material introduced into the tank with the carrier liquid, means associated with the impeller blades to draw downwardly into the open top of the impeller the solid material and carrier liquid above the impeller, and to place said liquid-borne solid material under the centrifuging influence of the impeller blades, for subjection of said material to the shearing action of the knives, said material after leaving the knives being circulated into the escape passageway behind the knives and directed upwardly along the tank side wall for re-entry into the open top of the impeller, a connector ring joining the upper ends of the blades on the rotating impeller, a second connecting ring joining all the stationary knives together, said second ring being disposed at substantially the same elevation as the first mentioned ring, and a series of vanes on the impeller above the connecting ring of the latter, for agitating and centrifuging material across both rings to scrub them continuously as the impeller rotates.

2. In a turbo-dissolver, the combination of a tank having a side wall and a bottom, a circular arrangement of stationary knives upstanding within the tank, said knives having upper portions in a common plane, and a connecting ring joining the upper portions of said knives, said ring and knives forming within the tank an open well, an open topped impeller fitted within the well

and arranged for rotation therein, said impeller comprising a series of radially disposed blades each extending outwardly to close proximity with the stationary knives, the outer ends of the blades including shearing edges angularly inclined to the stationary knife edges for effecting a shearing action upon any solid material in a carrier liquid undergoing processing within the tank, each impeller blade being inclined at an angle to provide a leading upper edge advanced in the direction of impeller rotation for drawing into the open top of the impeller the liquid-borne solid material aforesaid, the blades serving at the same time to centrifuge said material outwardly to the stationary knives, a connector ring joining together the blades of the impeller, and disposed at substantially the same elevation as the connector ring for the stationary knives, and a series of vanes on the impeller above the blade connector ring, for agitating and centrifuging material across both rings to scrub them continuously as the impeller rotates.

3. In a turbo-dissolver, the combination of a tank having a side wall and a bottom, a circular arrangement of stationary knives upstanding within the tank, said knives having upper portions in a common plane, and a connecting ring joining the upper portions of said knives, said ring and knives forming within the tank an open well, an open topped impeller fitted within the well and arranged for rotation therein, said impeller comprising a series of radially disposed blades each extending outwardly to close proximity with the stationary knives, the outer ends of the blades including shearing edges angularly inclined to the stationary knife edges for effecting a shearing action upon any solid material in a carrier liquid undergoing processing within the tank, each impeller blade being inclined at an angle to provide a leading upper edge advanced in the direction of impeller rotation for drawing into the open top of the impeller the liquid-borne solid material aforesaid, the blades serving at the same time to centrifuge said material outwardly to the stationary knives, a connector ring joining together the blades of the impeller, and disposed at substantially the same elevation as the connector ring for the stationary knives, and a series of vanes on the impeller above the blade connector ring, for agitating and centrifuging material across both rings to scrub them continuously as the impeller rotates, and means on the impeller inducing a similar scrubbing action upon the bottom of the tank included within the well aforesaid.

4. As a new article of manufacture, an impeller for a masticating and mixing machine, said impeller comprising a central hub and a series of blades radially extending from said hub, the outer ends of the blades presenting knife edges inclined relative to a plane that includes the hub axis, each blade further being inclined at an angle to provide a leading upper edge advanced in the direction of rotation of the impeller, relative to other portions of the blade, whereby upon rotation of the impeller the blades serve as a screw to draw mixable material toward the blades in position to be centrifuged outwardly by the blades, a top connector ring joining the blades in the region of their leading edges and a perforated shallow bottom wall beneath said ring joining together the lower portions of all said blades.

5. As a new article of manufacture, an impeller for a masticating and mixing machine,

said impeller comprising a central hub and a series of blades radially extending from said hub, the outer ends of the blades presenting knife edges inclined relative to a plane that includes the hub axis, each blade further being inclined at an angle to provide a leading upper edge advanced in the direction of rotation of the impeller, relative to other portions of the blade, whereby upon rotation of the impeller the blades serve as a screw to draw mixable material toward the blades in position to be centrifuged outwardly by the blades, a perforated shallow cone-shaped bottom for the impeller joining together the lower portions of all of said blades, and an upper connector ring joining the blades in the region of their leading edges, means in the form of sweep fins for centrifuging material along the impeller bottom, and a series of vanes on the connector ring above the blades, for agitating and centrifuging material laterally across the upper face of the ring.

6. In a machine of the class described, the combination of a tank having a side wall and a bottom, a series of stationary knives located within the tank and arranged in circular formation with the cutting edges of the knives upstanding relative to the tank bottom, thereby to form a circular well surrounded by knife edges, an impeller rotatably supported above the tank bottom within said well, and comprising a series of radially disposed blades having forwardly pro-

jecting shearing edges located at the outer ends of the blades to move in close proximity with the stationary knives as the impeller is rotated, thereby to comminute any solid material entering between the knives and blades, and means for rotating said impeller, said shearing edges being of a material harder and more durable than that of the impeller blades, and projecting forwardly in the direction of advancement of the impeller blades when rotating.

7. In a machine of the class described, the combination of a tank having a side wall and a bottom, a series of stationary knives located within the tank and arranged in circular formation with the cutting edges of the knives upstanding relative to the tank bottom, thereby to form a circular well surrounded by knife edges, an impeller rotatably supported above the tank bottom within said well, and comprising a series of radially disposed blades having shearing edges located at the outer ends of the blades to move in close proximity with the stationary knives as the impeller is rotated, thereby to comminute any solid material entering between the knives and blades, and means for rotating said impeller, said shearing edges comprising welds of hard and durable metal shaped to furnish sharp edges projecting in the direction of advancement of the impeller blades.
